UNITED STATES PATENT OFFICE.

FRANK A. McGINNIS, OF DETROIT, MICHIGAN.

DEVICE FOR STORING MEMORANDA.

No. 839,180.

Specification of Letters Patent.

Patented Dec. 25, 1906.

Application filed July 18, 1906. Serial No. 328,670.

To all whom it may concern:

Be it known that I, FRANK A. McGINNIS, a citizen of the United States, residing at Detroit, county of Wayne, State of Michigan, have invented a certain new and useful Improvement in Devices for Storing Memoranda; and I declare the following to be a full, clear, and exact description of the invention, such as will enable others skilled in the art to which it pertains to make and use the same, reference being had to the accompanying drawings, which form a part of this specification.

This invention relates to an improved device for the methodical arrangement of and the methodical storing of slips of paper or cards on which information has been entered.

In many lines of business the details of a transaction between a buyer and a seller or a debtor and a creditor are first recorded on a slip of paper or ticket, usually printed as a blank, to contain in print the always-repeated parts of the memorandum and with suitable rulings and blank spaces for those items or details which are peculiar to the special transactions. The specific parts of the transaction are subsequently copied into a record-book or journal. Such process is necessary in order to make a summation of an entire day's business and to keep a systematic account convenient for reference or record. From the record-books or journals further transcripts are made to ledgers or other auxiliary books and the original slips are usually packed up and stored away. In carrying a transaction of this kind through a set of books several entries, copies, or transcripts of the same transactions are necessary, and there is a liability to make errors in so doing, which liability to error my invention will reduce, if not eliminate altogether, by obviating the necessity for copying the slips of paper. This I accomplish by using the slips themselves for the entries, and, furthermore, the information entered on these slips of paper (needed in keeping accounts)—that is, filled in on the printed blanks at the time of transaction—can be produced on duplicate or triplicate slips of paper or tickets by the use of carbon-paper or manifolding devices, and it is apparent that when this is done my invention provides for the keeping of an entire set of books without making any entries whatsoever after the transaction is first recorded on the original slip of paper. For

illustration, one series of slips can be used in the holder designed for the cash-book, a second series in the holder designed for the journal, and the third series in the holder designed for the ledger, thus showing an account of an individual, firm, or corporation by the tickets of original entry in place of transcripts from them, and it has for advantages, first, that it prevents error; second, that it saves labor and time required to copy and also the time required to check back; third, that it saves the labor and time spent in wrapping the slips in packages and the time subsequently spent in unwrapping and searching for slips; fourth, the space required to store the slips and the various books made from them is greater than that required to store the slips when placed in my holder; fifth, the slips are only handled once instead of several times, and liability to loss of a slip is reduced.

The invention is especially useful in dealing with vouchers which evidence money transactions—as, for example, the vouchers which evidence the withdrawal from or deposit into a savings-bank of money or its equivalent, which contains the primary entry made by the person at the time the money is deposited or at the time money is withdrawn from a bank, may be arranged in orderly manner in the holder and used in place of the ordinary journal, cash-book, or ledger, or all of them, and may be subsequently preserved without rehandling and may be readily referred to at any time. Further, the slips when properly arranged in the holder contain the principal items of money amounts arranged in columns in proper order to be quickly added for checking purposes, and they may be arranged in orderly manner in the holder in less time than that which is required to copy the slips into a journal or record-book, thus not only preventing liability to error, but saving time. The same principle may be employed in keeping records in many other classes of business than that of banking, and it is especially applicable to the making of indexes, and for many business records where it is desirable to arrange items of information in tabular form.

To accomplish the desired end, the primary entries are made on slips of paper or cards which are printed to contain the always-repeated part of the contents and with blank spaces to contain items which are commonly

made in connection with the printed part. These slips are then arranged in holders made by plaiting a sheet of paper to form a number of pockets. The pockets are of equal depth and of a depth to cover and conceal that part of the slip which it is not necessary for the bookkeeper to examine or use and to leave the exposed part so arranged that it contains all that is necessary to be seen. To hold the slips securely in the pockets, the ends of the slips are covered by a flap that has rigidity enough to hold its position or may be even pasted or otherwise secured at intervals or throughout its entire length to the extreme ends of the slips.

In the drawings, Figure 1 shows the holder with slips contained therein. Fig. 2 is a section through the holder lengthwise the pockets. Fig. 3 is a section along the dotted line *a a* across some pockets that are covered by the holding-flap and across an uncovered part of other pockets. Fig. 4 shows a blank.

The holder 1 is made from a strip of flexible material, preferably paper folded into pockets, and with an edge binding 3 securing the ends of the folds and completing the pockets. Each strip 3 has an extension part 4, that is left free from the underlying pocket, and this extension-strip 4 may be covered at its ends 5 or throughout its entire extent on that face which lies adjacent to the pockets with adhesive material. If the strip be of reasonably stiff material, it will sufficiently secure the slips in the pockets if it be pasted or otherwise secured at its ends only; but if it be desired to hold the slips with still greater security the flap 4 may be in the first instance coated with a cement (like mucilage) and then pasted throughout its length upon the ends of the underlying slips or pasted at intervals upon small pieces of paper 11, inserted under a fold and under the flap. The slips 2 are preferably blanks suitable to any business with which the holder is employed and

of a length to fit accurately in the pockets 45 and to extend from one edge band to the other, with both ends under the projecting and securing flap.

In Fig. 2 is shown in cross-section the holder with flaps on both sides and at both 50 ends of each set of pockets. The flaps at the end 7 are shown as pasted down and at the end 8 as still free from the underlying slips, with the angle which they assume somewhat exaggerated. These holders with the contained slips may be stored in drawers, and thus be used as cards, similar to the cards of a card index, or they may, if desired, be fastened together by strings or other fasteners, either through holes 9 in the sides or through holes 55 10 at the ends.

What I claim is—

1. In combination with a sheet of flexible material plaited to form pockets, binding-strips at the edge closing and completing the 65 pockets, and a securing-strip adjacent to said binding-strip, substantially as described.

2. In combination with a sheet of flexible material plaited into pockets, an information-slip of a length to fill a pocket from end to 70 end, and a securing-strip held to the folded sheet and adapted to engage over the ends of the inserted information-slip, substantially as described.

3. In combination with a sheet of flexible 75 material plaited into pockets, a binding-strip at the edges closing and completing the pockets, an information-slip of a length to fill a pocket from end to end, and a securing-strip held to the folded sheet and adapted to engage over the ends of the inserted information-slip, substantially as described.

In testimony whereof I sign this specification in the presence of two witnesses.

FRANK A. McGINNIS.
